COLLAPSIBLE CORE.

1,105,737.

Specification of Letters Patent.

Patented Aug. 4, 1914.

Application filed December 21, 1912. Serial No. 738,053.

To all whom it may concern:

Be it known that I, JOHN K. WILLIAMS, citizen of the United States, residing at Akron, Ohio, have invented certain new and useful Improvements in Collapsible Cores, of which the following is a specification.

My present invention relates to improvements in collapsible cores or mandrels for manufacturing the outer casings or shoes of double tubed pneumatic tires having inextensible edges.

The invention has among others for its objects to provide a construction in which the number of parts shall be reduced to a minimum and be capable of being quickly and easily assembled and which when so assembled will be held firmly together and in accurate alinement.

A further object is to provide a core or mandrel capable of being readily applied to a tire building machine or stand in a properly centered condition, so as to rotste true thereon without necessitating any adjustments.

With these and other objects in view the invention includes the novel features of construction and arrangement and combination of parts hereinafter described and particularly defined by the appended claim.

A core constructed in accordance with my invention is illustrated in the accompanying drawings, in which—

Figure 1 is a side elevation of the assembled core, and Fig. 2 is a section on line 2—2 of Fig. 1. Fig. 3 is a section showing the mold in the core.

Referring by reference characters to this drawing, the numeral 1 designates the core which is preferably made hollow for lightness, and is of a size and shape corresponding to the tire shoe to be formed thereon.

In order that the core may be collapsible to effect its removal from the completed shoe, it is formed of a plurality of parts 1^a which, in the assembled form, abut each other to form the complete annular core, the line of junction between at least one of these parts and the adjoining portions being on lines oblique to the radii so that it may be withdrawn inwardly; thus allowing the remaining sections to also be withdrawn inwardly to effect the removal of the sections from the completed shoe.

In order that these sections may be readily assembled in their abutting position and

clamped together in accurate alinement and firmly held in such position, I provide each of them with an inwardly extending flange or rib. These inwardly extending flanges in the assembled condition form a complete annular bead or flange 2, which is provided on one side with an annular rib, 3 having the inclined face 3^a.

4 designates a single clamping ring which has an inclined face 4^a designed to coöperate with the face 3^a, the annular projecting portion of this ring being designed to rest in the recess formed behind the said inclined face 3^a. This ring 4 has a horizontally extending annular flange or portion 4^b which passes inside and forms a seat for the annular beading 2.

Rigidly secured to the core sections are a plurality of headless bolts 5, which are designed to pass through suitable openings in the ring, and are provided on their outer ends with nuts 6, by which the parts are firmly drawn together. By reason of the bolts being permanently carried by the core sections these latter are easily applied to the ring by relative lateral movement, and by reason of the inclined faces 3^a and 4^a the tightening of the nuts causes the sections to be drawn by this single clamping ring firmly against the inwardly extending annular flange or seat 4^b and thereby be held rigidly in position. The nuts 6 are preferably set into recesses in the ring, and may be tightened by an ordinary socket wrench. The flange 4^b is preferably carried laterally to an extent approximately equal to or exceeding the length of the bolts so that the projecting edge will serve as a seat and guide for the sections, thus enabling the bolt holes to be more readily brought into alinement with the bolts. On the side of the beading opposite to where the nuts are located, is located a rib or shoulder 7, which is in line with the edge 4^b of the ring when the latter is in place, which parts form a seat or guide for the mold sections 8.

Formed integral with the ring 4 is a spider comprising arms 8' and a central hub 9 adapted to be placed upon the shaft or axle of a tire building machine, and this hub may carry an integral gear 10 whereby it may be driven by power, or the gear may be used as a sprocket to be held against rotation by a pawl. By the use of such an integral spider the cost of production is greatly

2
reduced; the core is always properly centered without requiring adjustment, while the spider in no way interferes with the placing of the core and tire in a mold for curing.

Instead of having the bolts carried by the core sections, as shown in Figs. 1 and 2, I may have them carried by the ring, as indicated in Fig. 3, and passed through openings 10 in the core sections, the nuts being seated in recesses in the flange of the beading.

In assembling the collapsible core above described the bolts in each section are brought into alinement with the holes, 15 which is readily accomplished by bringing the edge of rib 3 into contact with the flange portion 4^b of the ring, after which the section may be slid laterally to cause the bolts to enter the bolt holes. Thereafter the 20 nuts are applied and tightened to draw and hold the section firmly in the position shown in the drawings, and the inclined faces tending to hold the section firmly against the ring or flange 4^b. This operation is re- 25 peated for each successive section until all are in place. In disassembling or collapsing the core after the tire has been formed

thereon the nuts are removed and the ring 4 removed from the sections by a lateral movement, after which the wedge shaped section 30 is withdrawn inwardly from the tire, allowing the other sections to be also withdrawn.

Having thus described my invention what I claim is:—

A device of the class described, comprising a cylindrical supporting member having an outwardly extending flange at one edge, and a plurality of segmental core sections having inner or base portions seating against said supporting member, said inner 40 portions having laterally extending ribs at one side engaging an annular groove in the flange at its base, and headless bolts for rigidly connecting said core sections and flange, said bolts being fixedly secured to 45 one of said parts and passing through openings in the other part.

In testimony whereof, I affix my signature in presence of two witnesses.

JOHN K. WILLIAMS.
